UNITED STATES PATENT OFFICE.

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA.

METHOD OF AND APPARATUS FOR SEPARATING LEAKS FROM TIGHT CANS.

Application filed November 7, 1923. Serial No. 673,394.

To all whom it may concern:

Be it known that I, ALBERT R. THOMPSON, a citizen of the United States, residing at San Jose, in the county of Santa Clara and

- 5 State of California, have invented certain new and useful Improvements in Methods of and Apparatus for Separating Leaks from Tight Cans, of which the following is a specification.
- 10 My invention relates, in general, to the canning art, and in particular to a method of and apparatus for separating the "leaks" from the "tight" cans.

My invention and apparatus, while 15 adapted for the detection and separation of defective cans, known in the art as "leaks," from the perfect or "tight" cans, in which products of any nature are hermetically sealed, are especially applicable to comestible filled cans, in connection with the cooling phase of the treatment, wherein while still under fluid pressure above atmospheric, the temperature of the cans is reduced prior to their discharge to the outer atmosphere.

20 25 By way of example I may mention the sterilizing of milk in hermetically sealed cans, the treatment of which comprises and includes as the final step the cooling of the cans in a chamber in which a fluid pressure above atmospheric is maintained. Another example is the common process of cooking and cooling sealed cans containing any food or other product, in which the final step is the cooling under pressure above atmospheric. To either of these examples my method and apparatus are particularly applicable and are utilized in connection with the discharge of the cans from the cooling effect.

30 35 40 45 50 In cooling, under pressure, product-filled, sealed cans, any leaky can is open to the entrance of the pressure medium, usually air. This has the effect of equalizing the pressure inside and outside the can, and consequently the moment the can is discharged from the cooler, and the pressure thereby relieved from the exterior of the can, the unbalanced internal pressure will at once cause the heads of the can to bulge, and this bulging condition will continue sufficiently long before the escape through the leaks of the excess of internal pressure, to enable the can to be distinguished from the tight cans,

the ends of which are not bulged. It is this differentiation upon which my invention is 55 based, and which results in the separation of the "leaks" from the "tight" cans.

My invention, therefore, consists essentially in automatically segregating the two kinds of cans, previously subjected to a cooling effect under fluid pressure, above atmospheric, according to the difference of end-bulge upon their release from said effect. It also consists in the successive steps of 60 and means for first subjecting the cans to 65 an external fluid pressure to provide preliminarily for the equalization of the pressure both inside and outside of the leaky cans, and secondarily to provide, upon the release of said pressure from the outside, 70 for the end bulging of said cans, and then automatically separating said end-bulged cans from the cans not so bulged, the latter being the tight cans.

In the accompanying drawings I show a 75 simple apparatus for separating the leaks from the tight cans according to my method.

It will be understood, however, that the method is not dependent upon nor confined to this apparatus, as other forms may be 80 used adapted for taking advantage of differences in size or shape.

Fig. 1 of the drawings is a side elevation, of the apparatus; partly broken in the upper portion of the can-selecting member. 85

Fig. 2 is a section on the line 2—2 of Fig. 1.

1 indicates supporting beams. 2 in Fig. 1 is a box or shell constituting a cooling effect. This may be of any suitable nature 90 such for example as is common in the art, in the so-called cookers and coolers. Through this cooler the cans pass in continuous procession and during their passage they are subjected externally to fluid pressure, above 95 atmospheric, said pressure being here shown as supplied by means of the compressed air connection indicated at 2'.

3 is a chute leading from the discharge of the cooler 2.

100 105 4 is a can selecting member mounted for rotation by means of a shaft 5 journaled in boxes 6 and driven by a pulley 7, as seen in Fig. 2. The selecting member 4 comprises spaced disks, the inner opposing faces of which are parallel at their inner zones

as shown at 4', and are flared or relatively divergent at their outer zones, as shown at 4''. The floor 3' of the chute 3 leads through between the disks, traverses their 5 parallel-walled inner region 4' and forms beyond said disks the floor of the lower delivery chute 8.

An upper delivery chute 9 has its floor 9' passing in between the disks in their 10 flaring-walled region 4'' and terminates on a line at the base of said region about at the beginning of its upper descending quadrant. 10, in Fig. 1, indicates the cans without distinction, as they pass from the cooler 15 2 into the chute 3.

10' are the cans which are tight and are not bulged; while 10'' are the cans known as "leaks," and which are end-bulged due to the unbalanced pressure as they leave 20 the cooler. The method carried out in this apparatus is as follows. The product filled cans are carried in continuous procession through the cooler 2 and are therein subjected to external pressure above atmospheric. 25 The leaky cans 10'' admit the pressure air to their interior and the pressure within and without is thus equalized. The tight cans 10' are not thus affected. As the leaky cans 10'' leave the cooler air and 30 are thus relieved from external pressure, their ends will bulge under their internal pressure which is not immediately released, since it takes appreciable time for the air to leak out. The tight cans 10' however 35 leave the cooler with non-bulging ends. In Fig. 1 the cans marked 10 shown coming from the cooler 2, may comprise all "leaks" or all "tights" or some of both kinds. When a "leak" 10'' reaches the disks of the selecting member 4 it passes into the flaring outer 40 region 4'', and on account of its bulging ends, it becomes lightly wedged in said region as seen in Fig. 2 and cannot pass down therein below the functional level 45 of the floor of the upper delivery chute 9, so that when, by the rotation of the disks, it reaches said floor it will pass out into the chute, as is shown in Fig. 1.

But when a "tight" can 10' reaches the 50 disks of the selecting member 4 it will, on account of its non-bulging ends pass freely across the flaring region 4'' of the disks and will continue along the floor 3', across the parallel inner region 4' of the disks 55 and across the opposite side of the flaring region and into the lower delivery chute, as seen in Fig. 1.

The "leaks" are thus detected and separated from the "tight" cans.

I claim:—

1. The method of separating the "leaks" 65 from the "tight" product-filled, sealed cans, comprising exposing the cans in a region under fluid pressure above atmospheric, adapted to equalize the external and internal pressure upon the "leaks"; discharging the cans from said region, to release the external pressure and cause the "leaks" to bulge their ends; and automatically segregating said cans according to the difference 70 of their end bulge.

2. In the treatment of products confined in hermetically sealed cans, the method of 75 separating the "leaks" from the "tight" cans comprising passing a continuous procession of cans through a cooling region under fluid pressure above atmospheric, adapted to equalize the external and internal pressure upon the "leaks"; discharging the procession of cans from said cooling 80 region, to release the external pressure and cause the "leaks" to bulge their ends; and passing said procession without interruption through a region in which the cans are automatically segregated according to the 85 difference of their end bulge.

3. An apparatus for separating the "leaks" from the "tight" product-filled sealed cans, comprising means for subjecting the cans to external fluid pressure above 90 atmospheric adapted to equalize the external and internal pressure upon the "leaks"; means for discharging the cans from said pressure means to release the external pressure and cause the "leaks" to 95 bulge their ends; and means for automatically segregating the cans according to the difference in their end bulge.

4. An apparatus for separating the "leaks" from the "tight" product-filled, sealed cans, comprising a cooling box through which the cans are passed in continuous 100 procession and from which they are discharged, said cooling box being under fluid pressure above atmospheric, whereby the 105 internal and external pressure on the "leaks" while in the box is equalized, and whereby upon their discharge and the release of external pressure said "leaks" bulge their ends; means coacting with the can ends for automatically dividing the can procession into 110 separate lines distinguished by a difference in their end-bulge; and means for separately delivering said divided lines.

In testimony whereof I have signed my 115 name to this specification.

ALBERT R. THOMPSON.
